W. F. SHOLL.
HANGER FOR CLOTHES LINES.
APPLICATION FILED APR. 24, 1916.

1,187,189.

Patented June 13, 1916.

UNITED STATES PATENT OFFICE.

WILLIAM F. SHOLL, OF HUBBELL, NEBRASKA.

HANGER FOR CLOTHES-LINES.

1,187,189.

Specification of Letters Patent. Patented June 13, 1916.

Application filed April 24, 1916. Serial No. 93,234.

To all whom it may concern:

Be it known that I, WILLIAM F. SHOLL, a citizen of the United States, residing at Hubbell, in the county of Thayer and State 5 of Nebraska, have invented certain new and useful Improvements in Hangers for Clothes-Lines, of which the following is a specification.

This invention is an improvement upon 10 the clothes line attachment for which Letters Patent No. 1,164,414 were granted to me December 14, 1915. This attachment is in the nature of a hanger and in the patent above referred to I disclosed a cross bar and 15 supporting hook, said bar being substantially midway the ends of the hanger. An objection to this feature is that unless the hanger was of considerable length its use was limited to comparatively small articles, 20 the cross bar interfering with the hanging of sheets, table cloths and like articles.

The present invention has for its object the elimination of this disadvantage without removing the central support.

25 The invention consists in the novel features of construction hereinafter described, pointed out in the claims, and shown in the accompanying drawings, in which:—

Figure 1 is a perspective view with my 30 present invention applied to the hanger. Fig. 2 is a face view of the said support, the hanger and clothesline being in section. Fig. 3 is a detail face view of the detachable end of the support. Fig. 4 is a perspective 35 view of said end. Fig. 5 is an end view of the hanger, opened to receive the clothesline.

In the drawings 1 is the line, 2 the hanger sides, 3 are end members one of which is extended to form a hook 4 to engage the 40 line, 5 and 7 are the opposite end members with the coöperating hooks 6 and 8. These parts are all included in the patent above mentioned.

The central support for this hanger comprises an inverted V-shaped frame 9 the 45 apex portion of which is bent to form an eye 10. One end of the support is provided with an eye which engages one side 2 of the hanger. The opposite end is bent at an 50 angle so that it will lie parallel to the opposite side of the hanger, and is then bent back on itself forming a bow portion, the bow portion being slightly curved inwardly with

respect to the hanger, the free end portion 14 extending back in a plane above and parallel to the portion 12. 55

When the support 9 is brought into proper position, being suspended from the line 1 by a hook 11, the part 12 lies below the side 2 of the hanger and the part 14 above, the 60 said side member resting on the inwardly curved bow portion, which engages the said side member. By means of this construction a sheet or any large sized cloth can be hung on this side member of the hanger, 65 extending from end to end thereof, and the free end of the support then brought into position, the sheet being caught between the parts 12, 13 and 14 of the attachment or support and the hanger side. A clothespin 70 can then be placed in position at this point, said pin engaging in its crotch the members 12 and 14, the sheet and the side member 2, thus securing all parts together. On removing the pin the free end of the support 9 can 75 be swung out of the way and the sheet or other article at once removed.

What I claim is:—

1. The combination with a hanger attachment for clothes lines, said attachment having side members, a support for said hanger comprising an inverted V-shaped wire member, one end of which is secured to one side member of the hanger and the opposite end of which is bent to lie in parallel relation to 85 the opposite side member, and means for securing the support to a clothes line. 80

2. The combination with a clothesline hanger having side members and supporting end members, of an intermediate support 90 therefor comprising a wire member arranged transversely with respect to the hanger and secured to one side of the hanger frame, a hook member carried by the support and adapted to engage a clothesline, 90 the free end of the support being angled and bent back upon itself forming a bow portion, said angled portion being adapted to lie parallel to the opposite side of the hanger, and the bow portion being curved 100 inwardly with respect to the hanger to receive the said side member.

3. The combination with a hanger of the kind described having side members, an inverted V-shaped supporting member, a hook 105 member carried by the apex of the support

ing member and adapted to engage a clothes-line, one end of the V-shaped member being secured to one side of the hanger, and the opposite end portion being bent at a right angle, thence upwardly and back upon itself, forming a bow portion, the bow portion being bent laterally, the members of said

bent portion when in position for use lying respectively in planes above and below the opposite side of the hanger, the said side 10 member of the hanger engaging said bow portion.

In testimony whereof I affix my signature.

WILLIAM F. SHOLL.
